Primary Examiner — Marissa J Cash(74) *Attorney, Agent, or Firm* — Johnson, Marcou & Isaacs, LLC(57) **CLAIM**

I claim the ornamental design for an aircraft nose, as shown and described.

DESCRIPTION

FIG. 1 is a side view for an aircraft nose, showing the new design, a side view of the reverse side is a mirror image of the illustrated side;

FIG. 2 is a front view of the aircraft nose; and,

FIG. 3 is a bottom view of the aircraft nose.

The broken lines shown in the drawings illustrate portions of the aircraft that do not form part of the claimed design.
